Screen Shot from the Art of Shaving Website “www.theartofshaving.com” visited on Feb. 22, 2007 showing 3 razors “5 blade Black & Nickel”, “5 blade Ivory & Nickel”, and “Engraved Razor” (in color, 3 pgs.).

Primary Examiner—Jennifer Rivard

(74) *Attorney, Agent, or Firm*—Kevin C. Johnson

(57) **CLAIM**

The ornamental design for a razor handle, as shown and described.

DESCRIPTION

FIG. 1 is a top perspective view of a razor handle showing our new design;

FIG. 2 is a top plan view thereof;

FIG. 3 is a right side elevation view;

FIG. 4 is a bottom plan view thereof;

FIG. 5 is a left side elevation view thereof;

FIG. 6 is a front elevation view thereof; and

FIG. 7 is a rear elevation view thereof.

FIG. 8 is a top perspective view of a razor handle showing our new design;

FIG. 9 is a top plan view thereof;

FIG. 10 is a right side elevation view;

FIG. 11 is a bottom plan view thereof;

FIG. 12 is a left elevation view thereof;

FIG. 13 is a front elevation view thereof; and,

FIG. 14 is a rear elevation view thereof.

The broken line disclosure of the shaving unit is for illustrative purposes only and does not constitute a part of the claimed design.

1 Claim, 8 Drawing Sheets
